UNITED STATES PATENT OFFICE.

HENRY IWAN AND LOUIS IWAN, OF STREATOR, ILLINOIS.

TILE-DITCHING HOE.

SPECIFICATION forming part of Letters Patent No. 320,136, dated June 16, 1885.

Application filed March 23, 1885. (No model.)

To all whom it may concern:

Be it known that we, HENRY IWAN and LOUIS IWAN, citizens of the United States, residing at Streator, in the county of La Salle 5 and State of Illinois, have invented certain new and useful Improvements in Tile-Ditching Hoes; and we do hereby declare that the following is a full, clear, and exact description of the same, reference being had to the 10 annexed drawings, making a part of this specification, and to the letters and figures of reference marked thereon.

Figure 1 of the drawings is a perspective view of our improved ditching-hoe complete; 15 Fig. 2, a similar view of the tubular socket and handle connected thereto, and Fig. 3 a perspective view of the bifurcated shank.

The present invention has relation to that class of ditching-hoes having a concavo-convex blade and a bifurcated shank or bail connected to the blade midway of its ends, so as to allow it to project out at each side of the shank. Previous to my invention this bifurcated shank or bail, to which the blade 25 of the hoe was secured, was cast or otherwise similarly formed with means for connecting thereto the end of the wooden handle. It was further common to construct this bifurcated shank in two sections terminating at 30 their upper ends in ratchet-faced clamps, and secured to a similarly-formed head on the lower extremity of the tubular socket by a bolt, the object thereof being to adjust the blade of the hoe at any desired angle with relation to the handle.

It is the object of the present invention to improve the construction of the above-mentioned class of hoes, which I attain by forming the bifurcated shank in one piece 40 with a ratchet-head and the tubular socket with a correspondingly-formed head and connecting the two by a suitable bolt, as will be hereinafter described and claimed.

In the accompanying drawings, A represents the blade of the hoe, and B the bifurcated shank or bail, terminating at its lower ends in ears *a*, for attaching it to the sides 45 of the blade by suitable rivets or other like fastenings. This shank B differs from others 50 of its kind in that it is formed in one and a single piece with the ratchet-faced head C.

The ratchet of the head C engages with a similar-formed head, D, cast or otherwise formed on the lower extremity of the tubular socket E, to which the end of the wooden handle F is inserted and fastened. The ratchet side of the head D is formed with a segmental bearing shoulder, *b*, for the head C, so that when using the hoe the strain is taken off of the screw-bolt *c*, which connects the two heads 60 together, a nut, *d*, being used upon the screw-threaded end of the bolt to draw the ratchet-faces of the heads in engagement with each other to hold the blade A to the angle adjusted.

The shank B with its ratchet-head C being made in one piece greatly lessens the cost of manufacture, and also possesses increased strength, while fewer parts are necessary to enable a perfect adjustment of the hoe-blade, 70 and consequently less liable to get out of order, these features of superiority being considered of much importance in this class of hoes, as it is necessary that when the blade is set to the angle required it shall remain firm 75 and rigid, to resist the strain upon the blade when working with the hoe, which is not always the case where the bifurcated shank is formed in sections, the sections at their ratchet ends spreading apart and becoming 80 disengaged with the ratchet-head on the handle.

It is evident that in place of the tubular socket E the ratchet-head C may be formed on the end of a suitable tang pointed at its 85 end to enter the end of the wooden handle; or the ratchet-head may be provided with any well-known means for connecting it to the handle, these changes being obvious ones and coming within the scope of our invention.

Having now fully described our invention, what we claim as our invention, and desire to secure by Letters Patent, is—

1. As an improved article of manufacture, a bail having integrally formed therewith 95 a ratchet-head at substantially right angles to the plane of the bail, its ends expanded to form ears, in combination with a handle having a ratchet-head corresponding to the ratchet-head of the bail, substantially as shown, 100 and for the purposes described.

2. As an improved article of manufacture,

a ditching-hoe consisting of a concavo-convex blade, a bifurcated shank or bail connected to the sides of the blade, and a ratchet-head formed integral with the bail and at 5 right angles to its plane, in combination with a handle provided with a ratchet-head corresponding to the head of the bail, and having a segmental bearing-shoulder, as and for the purposes described.

In testimony that we claim the above we do have hereunto subscribed our names in the presence of two witnesses.

HENRY IWAN.
LOUIS IWAN.
